US00D768311S

(12) **United States Design Patent** (10) Patent No.: **US D768,311 S**
Marshall (45) Date of Patent: ** Oct. 4, 2016

(54) **REMOTE CONTROLLER FOR VIBRATORS**

(71) Applicant: **Ian Peter Marshall**, Kettering (GB)

(72) Inventor: **Ian Peter Marshall**, Kettering (GB)

(73) Assignee: **ROCKS OFF LIMITED**

(**) Term: **15 Years**

(21) Appl. No.: **29/546,115**

(22) Filed: **Nov. 19, 2015**

(30) **Foreign Application Priority Data**

Jun. 18, 2015 (EM) 002721340-0005

(51) **LOC (10) Cl.** **28-03**

(52) **U.S. Cl.**

USPC **D24/215**

(57) **CLAIM**

The ornamental design for a remote controller for vibrators, as shown and described.

DESCRIPTION

FIG. 1 is an isometric view of the remote controller for vibrators showing my new design;

FIG. 2 is a left view thereof;

FIG. 3 is a right view thereof;

FIG. 4 is a top plan view thereof;

FIG. 5 is a bottom view thereof;

FIG. 6 is a front view thereof; and,

FIG. 7 is a rear view thereof.

1 Claim, 6 Drawing Sheets

FIG. 1

FIG. 2

FIG. 3

FIG. 4

FIG. 5

FIG. 6

FIG. 7
